SHEET LEVELER

Hans Birkle, Siegen, Germany, assignor to Siegner Maschinenbau G.m.b.H., a corporation of Germany

Filed Nov. 17, 1964, Ser. No. 411,751

Claims priority, application Germany, Nov. 29, 1963,

S 88,486

1 Claim. (Cl. 72—162)

This invention relates to a sheet leveler having straightening rolls or roll trains received in a frame, the rolls being adjustable in relation to one another, whereby the material to be leveled is passed between the rolls and straightened by directionally alternating and gradually diminishing the deformations imparted to the material.

One design of a leveling machine known in the art included an upper train of straightening rolls mounted in a vertically adjustable crossbeam which is received in a frame. Also included is a lower train of straightening rolls preferably secured in a second frame. The outer top straightening rolls are constructed to be vertically adjustable independently of the other rolls. In such a leveler, deformation of a sheet, for example, passing between the first pair of rolls can be reduced to a lower value and by corresponding vertical adjustment of the last straightening roll, the final sheet deformation can be regulated so that the sheet travels in a direction straight out of the straightening rolls.

In another sheet leveler the upper train of straightening rolls is not only vertically adjustable but also arranged to be horizontally swingable with respect to one another. In this leveler the sheet is heavily deformed at the entry side and, in accordance with the clearance angle, the sheet deformations are decreasing from roll to roll. Permanent deformation beyond the yield point occurs only between the first pair of straightening rolls at the entry side while the deformations effected by the succeeding pairs of straightening rolls gradually diminish towards a zero value.

With respect to the first mentioned leveler, permanent deformation is achieved by all the pairs of straightening rolls whereby a sheet leveled with this machine contains considerable residual stresses that may disturb subsequent processing. In the last mentioned sheet leveler difficulties arise upon entrance of the sheet between the leveling rolls, especially in the case of heavier degrees of sheet deformation, because the first pair of rolls must perform the heaviest deformation work. In addition, this leveler requires a relatively large number of straightening rolls to obtain the desired degree of leveling.

To eliminate the disadvantages of known sheet levelers, the present invention provides a leveler in which one of the opposite trains of rolls is adjustable in relation to the other train through translational movement relative to the straightening plane. The rolls in said one roll train are arranged in two groups and carried by separate frames. At least one of these roll groups is adjustable independently of the other one through swinging of its frame about an axis lying within the leveler and preferably in the central plane thereof. The invention also provides that the said two groups of rolls have the same number of straightening rolls. In addition, it is advantageous to organize both groups of rolls mechanically independent of each other for horizontal swinging movement so as to permit any degree of adjustment for both groups.

The positioning of the frames carrying the two groups of straightening rolls is advantageously so developed that the swivel axes of the frames coincide with the centers of rotation of two inner adjacent straightening rolls of each frame.

2

Another feature of the present invention relates to providing individually adjustable pivot drives for both groups of rolls that make up one roll train and an individual vertical adjustment drive for the other roll train. Means are provided for coupling together the pivot drives of the two roll groups in the form of a coupling or an interposed transmission member so that both simultaneous and individual adjustment of the straightening rolls may be accomplished. Thus, upon reverse operation of the drives, the existing angles of traverse of the roll groups at the entry and delivery side may be automatically adjusted when a sheet is to be leveled while traveling in the reverse direction.

Further advantages may be obtained when one of the intermediate straightening rolls or a backup roll associated therewith has its own adjusting system independent of the adjustment of the other straightening roll. By adjustment and/or selection of the shape of the backup roll, corrections can be made for partial stretching of a sheet to be leveled.

In a variant arrangement of the present invention, there is provided one roll train fixedly arranged in the leveler frame while the other roll train received in two frames is arranged to be both vertically adjustable in a direction normal to the straightening plane and horizontally swingable. It is preferred, however, to employ an undivided roll train vertically adjustable in relation to the straightening plane, and as to the other train, it is divided into two groups, pivotally supported within the leveler frame about different centers of rotation.

The foregoing features of the invention, as well as others, will become more evident from the following description and the attached drawings of which:

FIGURE 1 is a schematic elevational view of a sheet leveler illustrating one embodiment of the present invention;

FIGURES 2 and 3 are force diagrams of two variable adjustments of the sheet leveler according to the invention; and

FIGURES 4 and 5 are force diagrams corresponding to FIGURES 2 and 3, but representative of known sheet levelers.

With reference now to FIGURE 1, there is illustrated one side of a sheet leveler which includes a housing 1. Positioned within the upper portion of a window formed in this housing is a vertically adjustable frame 2 which rotatably receives a train or plurality of straightening rolls 3. In order to simplify the disclosed embodiment of the present invention, backup rolls usually employed above the straightening rolls 3 are not shown in the drawings. The lower portion of the housing window is formed with two opposed segmental surfaces onto which there are positioned circular segmental frames 4 and 5 that rotatably receive a number of straightening rolls including rolls 6, 8 and 7, 9. Between these rolls and the train of rolls 3 passes a plane hereinafter referred to as the "straightening plane." The segment frames 4 and 5 each swing about pivot points which are near the straightening and central vertical planes of the leveler. In the illustrated embodiment the pivot points of the frames 4 and 5 coincide with the rotational axes of the rolls 8 and 9, respectively.

Operatively connected to the frames 4 and 5 are pivot drives having motors 10 and 11, worms 12 and 13, and worm wheels 14 and 15, respectively. Arranged on the shafts of the worm wheels are cams 16 and 17 which are received into bores formed in sliding blocks 18 and 19 that are in turn received in guides 20 and 21, respectively.

Referring now to the frame 2 there is provided within the housing 1 a screwdown 23 to adjust the vertical

position of the frame. This screwdown is made up of a worm 24 and worm wheels 25 and 26 that are connected to screws 27 and 28, respectively. The screws engage the frame 2 and determine the height of the frame and train of rolls 3 carried thereby.

With particular reference to the train of rolls 3 and to the central roll identified as 29, there is provided a backup roll 30 received in a yoke 31 which is in turn received in the frame 2 as shown in FIGURE 1. A separate vertical adjustment is provided for the roll 30 which includes a worm 32 connected to a worm wheel 33 received on a screw 34.

In the operation of the sheet leveler, the illustrated embodiment shows a sheet 22 passing from right to left as one views FIGURE 1, coincident with the straightening plane and trains of rolls 3 and 6, 8 and 7, 9, respectively. Adjustment of the upper trains of rolls 3 and of the two roll groups 6, 8 and 7, 9 may be selected so that in the straightening plane in the area of the roll group 7, 9 the sheet is flexed upwardly and downwardly to such a degree that plastic deformation of the sheet extends not only to the external sheet surface, but it is carried out close to the neutral fiber, so that the sheet is prepared accordingly for the actual straightening effect. The group of straightening rolls 6, 8 are positioned by the cam 16 so that deformation of the sheet diminishes toward zero as the sheet passes from the last straightening roll 6 at which time it is completely leveled. The residual stresses imposed by the plastic deformation in the zone of the roll group 7, 9 are completely relieved by the alternative bending with decreasing magnitudes in the zone of the roll group 6, 8.

Certain advantages of the present invention may be more fully appreciated by viewing FIGURES 2 through 5 in which each figure represents a diagram of the forces exerted upon a sheet being leveled. In the interest of a simplification the average values of the forces acting on the sheet within a leveler have been represented in the diagrams, therefore the diagrams do not represent the changing directions of the forces nor their pulsations during the passage of the sheet between the straightening rolls.

FIGURE 2 shows a force diagram of the forces imposed on a sheet when the rolls of the leveler are adjusted as illustrated in FIGURE 1. When entering the leveler, the sheet is subjected to rapidly rising forces created by the foremost rolls of the group of straightening rolls 3 and 7, 9. When the forces reach a maximum in magnitude, the forces upon the sheet are adequate so that alternating plastic deformation is achieved.

The initial increasing forces are represented at 35 in FIGURE 2 and correspond to the entrance of the sheet in the leveler. The zone of maximum forces is represented at 36 while decreasing sheet deformation forces are represented at 37.

These decreasing forces occur when the end of the frame 4 carrying the straightening roll is slightly lowered with respect to the horizontal, so that from the straightening roll 8 in the direction of the roll 6 the deformations decrease linearly towards a zero value sufficiently so that the sheet emerges from the rolls 3 and 6, 8 fully straightened.

In the event it is desired to obtain greater sheet deformations, the train of rolls 3, including roll 29, are positioned in a downward direction by adjusting the screwdown 23. The group of straightening rolls 7, 9 are then positioned at an incline or further inclined to the horizontal plane by adjustment of the pivot drive motor 11. The inclination of the rolls 7, 9 being such that the roll 7 is lower in elevation than roll 9. With the straightening roll so positioned, the forces imposed upon a sheet being leveled are represented by the diagram in FIGURE 3. The line 38 represents the forces upon the sheet during its entry into the leveler. It will be noted that the magnitude of these forces is less than the forces repre-

sented at 35 in FIGURE 2. Line 39 represents the increasing forces that result in a plastic deformation. These forces become greater in magnitude than those represented at 36 in FIGURE 2 and result in greater sheet penetration of the plastic deformation forces. Finally, in FIGURE 3, line 40 represents a decrease toward zero in magnitude of forces upon the sheet. It is to be appreciated that the decrease in forces upon a unit of sheet length occurs, with respect to the embodiment illustrated in FIGURE 1, after the sheet unit has passed from rolls 29 and/or 8.

For the sake of comparison, force diagrams of conventional sheet levelers are shown in FIGURES 4 and 5.

The diagram illustrated in FIGURE 4 represents the forces imposed upon a sheet passing through a leveler having trains of straightening rolls adjustable in relation to one another and a separately adjustable straightening roll arranged at the first and last positions of one roll train. In FIGURE 4 a relatively steep line 41 represents the forces upon the sheet when entering the leveler. This line is followed by an extended zone of alternative deformations represented at 42, which are constant in magnitude so that the plastic deformation per se appears to be adequate. However, the forces upon the sheet passing from the leveler represented at 43 are reduced rapidly, and as a result, the last back-flexure of the sheet is straightened out without, as would be desirable, imposing alternative sheet deformations with diminishing magnitude.

In the diagram of FIGURE 5 the sheet flexing forces are imposed by the sheet leveler in which two opposite roll trains are vertically adjustable and also horizontally shiftable in relation to one another. In this type of leveler, an acute disadvantage is the very rapid increase in the forces upon the sheet as represented by the line 44. This limits the amount of sheet deformation obtainable by such a leveler. After the sheet passes the first pair of rolls, deformation of the sheet diminishes slowly and without the plastic deformation. Such deformations are required, however, for the removal of stress in the ideal straightening process.

With respect to the known sheet leveler arrangement characterized by the force diagram in FIGURE 5, it is necessary to provide a relatively large number of straightening rolls in order to achieve adequate straightening and stress relieving of the sheet. The sheet leveler according to the present invention will obtain the desired properties in the leveled sheets by employing a smaller number of straightening rolls than sheet levelers based on the design according to the diagram of FIGURE 5. Furthermore, sheet levelers according to the present invention are more versatile and adaptable to a wider range of sheets and the like, so that, for example, difficulties during the run-in of the sheets can be avoided when heavier sheet deformations are to be performed.

With reference now to the embodiment illustrated in FIGURE 1, as previously noted, a means is provided to deflect the straightening roll 29 so as to effect a working or stretching of a portion of the sheet being leveled. This is accomplished by controlling the manner in which the straightening roll 29 is supported so as to control its deflection. Such working or stretching, for example, can be advantageously employed to remove an unflat or wavy condition of the strip being leveled. The unflat condition is created when one portion of a sheet is longer than an adjacent transverse portion. The means for controlling the deflection of the roll 29 includes the backup roll 30 which is brought into contact with the straightening roll 29 by the screw 34 so as to control the deflection of the roll 29. In the case under discussion, the working or stretching effect is exerted primarily upon the middle portion of the sheet, thereby this portion will be elongated which will reduce or eliminate the waviness, in addition to improving the overall results in the leveling process.

If, as illustrated in FIGURE 1, the backup roll 30 is substantially shorter than the straightening roll 29

and its position with respect to the roll train 3 is not altered by the screwdown parts 32, 33 and 34, the result will be a simple deformation without partial stretching. If, on the other hand, the backup roll 30 is retracted by its screwdown, it will bend upwardly under the strain 5 of the sheet being straightened, so that the outer edges of the sheet to be straightened are stretched.

As heretofore indicated, variations of a sheet leveler according to the present invention can be obtained by employing the swingable frames 4 and 5 which receive the groups of straightening rolls 6, 8 and 7, 9 above the straightening plane and providing adjustment relative to height. Additional straightening rolls can be provided in a frame arranged intermediate the swing frames that receive the straightening rolls.

The roll adjusting devices, i.e., screwdowns and pivot drives of the sheet leveler are preferably coupled together by control elements arranged ahead of the leveler. In addition, it may be advantageous, with respect to reversible sheet levelers, to exert control of the pivot drives in such a manner that when the leveler is operated in the reverse direction, the pivot drives are reversed automatically, so that its angular position of the frame 5 at the entry side can be obtained at the delivery side, while the angular position of frame 4 is transmitted to the entry side of this leveler. In this respect, it may be advisable to couple the two pivot drives to indicate mechanically the settings in such a way that, through a common adjusting process, alternative adjustment of the setting angles is effected.

In certain forms of the present invention, it may be desirable to provide a machine crown on the backup roll 30 to improve the overall results of that portion of the present invention addressed to reducing or eliminating the unflat condition of the strip, whether it be in the center of the strip or on the two edges thereof.

In accordance with the provisions of the patent statutes, I have explained the principle and operation of my invention and have illustrated and described what I consider to represent the best embodiment thereof. However, I desire to have it understood that within the scope of the appended claim, the invention may be practiced otherwise than as specifically illustrated and described.

I claim:

In a leveler for straightening sheet material and the like comprising:

a housing having a window formed therein;

first and second trains of straightening rollers, each

10
15
20
25
30
35

comprising a plurality of spaced-apart rollers received in said window; said first train arranged in an opposed relationship with respect to said second train so that the rollers of each train are arranged in a nested relationship, said opposed trains of rollers being arranged to form a straightening plane therebetween; a first frame received in said window for rotatably supporting said first train of rollers; a screwdown carried by said housing for positioning said first frame and the rollers carried thereby in a direction normal to said straightening plane; second and third frames pivotally received in said window for rotatably supporting said second train; means for positioning said second and third frames about axes lying near to the point of intersection of the vertical center plane of the leveler and the straightening plane, whereby selective positioning of the rollers of said second and third frames relative to the rollers of said first train creates alternatively first and second zones, one being of an appreciable length wherein high sheet deformation takes place and the other a zone of gradual varying deformation; a single backup roller arranged with its axis coinciding substantially with the vertical center plane of said leveler and engageable with one of said straightening rollers of said first train to control the shape thereof along its axis for differentially stretching a sheet being leveled to reduce waviness in the sheet; and a second screwdown for adjusting the backup roller relative to said one straightening roller of said first train.
